UNITED STATES PATENT OFFICE.

GEORGE W. THOMPSON, OF CHEBOYGAN, MICHIGAN, ASSIGNOR TO BIFLEX PRODUCTS COMPANY, A CORPORATION OF DELAWARE.

CONTROLLING MEANS FOR IGNITION CUT-OFFS.

Application filed January 22, 1920, Serial No. 353,174. Renewed October 13, 1926.

My invention is an improvement in ignition cutoffs, and has for its object to provide a device of the character specified, especially adapted for use in connection with the ignition systems of internal combustion engines, for interrupting the circuit, and wherein the cutoff is controlled by the pressure of the oil in the oil line.

In the drawings:

10 Figure 1 is a vertical section through the controlling mechanism of the cutoff;

Figure 2 is a section at right angles to Figure 1;

15 Figure 3 is a section on line 3—3 of Figure 2;

Figure 4 is a sectional view taken on the line 4—4 of Figure 1.

In the present embodiment of the invention, a cylinder 1 is provided having heads 20 2 and 3 at its opposite ends, and the cylinder is provided with bracket lugs 4, by means of which it may be secured to the dash-board 5 of a motor vehicle for instance.

25 A plunger 6 is arranged within the casing constituted by the cylinder and the heads, and this plunger which has the usual packing rings has connected therewith a stem or rod 7 which extends through a packing in the head 2.

30 A coil spring 8 is arranged between the head 2 and the plunger and acts normally to force the plunger downward. The cylinder 1 is interposed in the oil line of the motor not shown, and the said cylinder has an inlet 9 and an outlet 10 for the oil, the outlet being spaced above the inlet, as shown, and when there is no pressure in the cylinder beneath the plunger the spring will force the plunger down cutting off the intake from 35 the outlet.

40 A shaft 11, which controls the cutoff switch not shown is journaled in the dash-board 5, and this shaft has a crank arm 12 in front of the dash-board, which is connected to the stem 7 of the plunger by a link 45 13. As shown, the link is longitudinally slotted, and the crank arm has a pin 14 engaging in the slot providing a lost motion connection between the crank and the plunger. A head 15 is secured to the shaft 11 in front of the dash-board, and a coil spring 16 is arranged in the recess 17 in

the front face of the dash-board about the shaft, the spring bearing at one end against a stop on the shaft, and at the other end 55 against an escutcheon 18 on the dash-board. The spring holds the button or knob 15 in close contact with the escutcheon.

The operation of the device is as follows:

The ignition circuit not shown of the internal combustion engine with which the present device is associated should be so arranged or connected that upon the arm 12 being brought to a raised position as shown in Figure 2 of the drawings, the ignition 60 circuit will be closed and upon this arm being drawn downwardly or lowered the ignition circuit should be opened. Assuming this to be the case when oil pressure exists in the lower end of the cylinder 1 the plunger 6 will be forced upwardly until the opening 10 is uncovered and will remain in this position as long as the pressure of oil is maintained therebeneath. The spring 16 will 65 yieldingly hold the shaft 11 in its adjusted 70 position. When the pressure of the oil falls below a predetermined point the spring 8 will force the plunger downwardly shutting off the oil supply through the opening 10 and the link 13 will simultaneously draw 75 downwardly the arm 12 to such a position 80 that the ignition circuit will be opened. So long as the pressure in the oil line is at a predetermined degree the ignition circuit 85 may be maintained closed. It is therefore impossible to operate the engine of the motor vehicle unless there is sufficient oil for lubricating the different parts of the same. The present device also makes it impossible to 90 leave the ignition current on when the engine is not running.

I claim:

A device of the character described comprising a cylinder having an inlet adjacent its one end adapted to be connected to an oil pump of an internal combustion engine and having an outlet intermediate its ends, a spring-pressed piston within the cylinder adapted to normally prevent communication between the inlet and outlet of the cylinder and adapted to move within the cylinder under influence of oil pressure from said pump and assume a position for establishing communication between the said inlet and

outlet, a rotatable rod, a lever or arm extending from the rod, means associated with the rod whereby said rod will be yieldably held against rotation, a slotted link having 5 one end pivotally connected to the piston, a pin carried by the arm upon said rotatable rod and slidably in said slot, and said slot

being of such length that when the arm is in one of its adjusted positions and upon the piston assuming its normal or closed position the shaft carrying said arm will be rotated a predetermined degree. 10

GEORGE W. THOMPSON.
